ADVERTISING DISPLAY DEVICE

Raymond O. Paul, Chicago, Ill.

Application January 18, 1956, Serial No. 39,825

Term of patent 14 years

(Cl. D1—2)

Fig. 1 is a front perspective view of an advertising display device showing my new design;

Fig. 2 is a side elevational view; and

Fig. 3 is a rear elevational view thereof.

I claim:

The ornamental design for an advertising display device, as shown.
